UNITED STATES PATENT OFFICE.

ARTHUR J. CRIPPEN, OF ROCHESTER, NEW YORK, ASSIGNOR TO CRIPPEN RECORD FILE CORPORATION.

DISK-RECORD CABINET.

1,375,085.

Specification of Letters Patent. Patented Apr. 19, 1921.

Application filed January 25, 1916. Serial No. 74,106.

To all whom it may concern:

Be it known that I, ARTHUR J. CRIPPEN, of Rochester, in the county of Monroe and State of New York, have invented certain new and useful Improvements in Disk-Record Cabinets; and I do hereby declare the following to be a full, clear, and exact description of the same, reference being had to the accompanying drawings, forming a part of this specification, and to the reference-numerals marked thereon.

The present invention has to do with cabinets of the type commonly employed for housing disk records that are used on sound reproducing machines, where the records are maintained in a vertical position, preferably, and are controlled by ejecting mechanisms that may be operated when it is desired to discharge a selected record from the cabinet, and my improvement has for an object to afford a simplified form of ejecting mechanism, composed of a minimum number of parts and so combined as to insure complete efficiency under all operating conditions. A further purpose of the invention is to afford a practicable construction which can be manufactured at a reasonable cost, with provision for arranging a maximum number of records in a given space and at the same time permitting the records to be removed quickly and with little difficulty. To these and other ends the invention consists in certain improvements and combinations of parts, all as will be hereinafter more fully described, the novel features being pointed out in the claims at the end of the specification.

In the drawings:

Figure 1 is a vertical sectional view showing the application of my invention to one style of cabinet;

Fig. 2 is a vertical sectional view with the parts enlarged and showing the position of the ejecting device at the limit of its outward movement when a record is discharged from the cabinet;

Fig. 3 is a horizontal sectional view in the plane of line 3^a—3^a of Fig. 1;

Fig. 4 is a front elevation of a cabinet, and

Fig. 5 is a sectional view on line 5^a—5^a of Fig. 1.

Similar reference numerals in the several figures indicate the same parts.

The invention is susceptible of a number

of different embodiments, one of which is illustrated in the present application and includes a casing having top and bottom walls 1 and 2 and extending therebetween are a series of vertical partitions or walls 3. The latter are held in place by spacing strips 4, which embrace opposite sides of the top and bottom edges of the partitions and are maintained in such relation thereto by means of suitable holders or frames 5 extending between the side walls of the casing to which they are attached, and provided with inclined flanges 6 at their front and rear edges that serve to maintain the partitions and spacing strips in proper relation. The structure which I have thus far described does not form any essential part of the present invention, and constitutes substantially what is covered in my Letters Patent No. 1,267,981, granted May 28, 1918.

Extending transversely of the casing between the side walls thereof is a bar or rod 7 which forms a support or bearing for a series of ejecting devices, one of which is disposed between each pair of adjacent partitions, that is, in each record compartment formed by adjacent partitions. Each ejecting device comprises an angle lever and is preferably in the form of an angle arm bent from wire, with its apex or upper portion pivotally arranged on the support 7.

The angle arm referred to comprises a forward portion 8, the extremity of which is bent at 9 to afford a nose for engagement with the edge of a record when the latter is to be discharged, while the rear portion 10 of the ejecting device is extended downwardly with its lower extremity arranged for co-operative relation with an actuating member that will now be described. Each actuating member includes a rod or bar 11 having an offset or elevated portion 12 at its rear end, which latter is provided with an elongated opening 13 that receives the extremity of the rear portion 10 of the ejecting device. The actuating members are disposed beneath the lower holder or frame 5, at the bottom of the cabinet, being arranged preferably in two tiers and in staggered relation, as shown in Figs. 1, 4 and 5, so that the record compartments may be arranged as closely together as possible with a view to minimizing the space required laterally for any given number of records.

Each actuating member is provided at its 110

forward end with a slightly enlarged head 14, those in the lower row or tier extending beyond those in the upper tier and affording a means for grasping the actuating member, which is drawn forwardly of the cabinet for ejecting a record. When an actuating member 11 is pulled forwardly, it moves the rear portion of the ejecting device also forwardly until it engages the stop bar 15, and at the same time the nose 9 of the actuating device is brought into engagement with the rear edge of the record, causing the latter to move forwardly until it is far enough removed from the cabinet 15 to be grasped. Rearward movement of the records within the cabinet is limited by means of stops 16, one of which is arranged in each compartment on a rod 17 that extends transversely of the casing and passes 20 through the several partitions.

One of the particular advantages of my improvement resides in enabling ejecting a record by drawing the actuating member outwardly, as distinguished from devices of this sort, by which it is proposed to push a key or operating member inwardly, and the reason for this is found in the fact that where the ejecting operation is outward, the heads of the actuating devices, or keys, need 25 not be so large, and in fact can be operated successfully when quite small, only sufficient size being required to permit a slight grip on the device. The arrangement therefore, it will be seen, permits a much larger 30 number of records to be contained in a space of a given width, and this also has a fur- 35

ther advantage of maintaining the records in closer and tighter relation, while still requiring no great effort to effect their removal. It will be recognized that the invention is not in any manner to be limited to the precise construction and arrangement described, and I intend to cover by this application any such modifications or changes as may properly come within the spirit of 40 the invention and the scope of the appended claims.

I claim as my invention:

1. In a disk record cabinet, the combination with a record compartment, of an ejecting device comprising a pivoted angle arm which extends downwardly from its pivotal point and includes a forward portion for engagement with the edge of a record and a downwardly projecting rear portion, and an actuating member arranged beneath the ejecting device and provided with an opening 50 in which engages the extremity of the rear portion of said angle arm.
2. In a record cabinet, the combination 60 of a plurality of record compartments, a rod extending through each of said compartments, a V-shaped ejector pivotally suspended from said rod in each compartment, a slideable actuator having an offset end 65 adapted to engage one arm of the ejector, and means for limiting the movement of the ejector.

ARTHUR J. CRIPPEN.
